UNITED STATES PATENT OFFICE.

OTTO FAHRNI, OF BLUMLIMATT, NEAR THUN, SWITZERLAND, ASSIGNOR TO GOTTLIEB RIESER AND LEOPOLD WYLER, BOTH OF BERNE, SWITZERLAND.

AUTOMATIC OPERATING DEVICE FOR EMBROIDERY MACHINES.

Application filed April 15, 1918. Serial No. 228,572.

To all whom it may concern:

Be it known that I, OTTO FAHRNI, a citizen of the Swiss Confederation, and residing at Blumlimatt, near Thun, Switzerland, 5 have invented certain new and useful Improvements in Automatic Operating Devices for Embroidery Machines, of which the following is a specification.

This invention relates to improvements in 10 embroidery machines and particularly to improvements in automatic operating devices for embroidery machines in which the simultaneous vertical and horizontal displacements of the frame that jointly determine the movement (or shifting) of the 15 frame, are regulated for each stitch by means of holes formed in a perforated pattern strip. This invention will be understood from the embodiment thereof hereininafter particularly described and comprising 20 a lever to which is attached a rack serving indirectly to actuate the frame and which, through the intermediary of a series of two-armed levers (or bell-cranks) is so connected 25 with a series of cranks having different lengths and adjustable independently of one another in two positions opposite one to the other, that each crank exerts or produces upon the rack a shifting (or displacement) 30 thereof corresponding to the throw of the crank.

In the drawings illustrating the principle 35 of this invention and the best mode now known to me of applying that principle, Fig. 1 is a top view from the upper half of which the topmost part of the driving mechanism is omitted. Fig. 2 is a side elevation, in which some parts are shown in section. Figs. 3 and 4 are diagrammatic views of 40 certain details hereinafter referred to. Fig. 5 is a detail illustrating parts shown in Fig. 2. Fig. 6 is an end elevation viewed from the left-hand side of Fig. 2. Figs. 7 to 11 and Figs. 13 and 14 illustrate details hereininafter described. Fig. 12 and Figs. 15 to 29 are working diagrams hereinafter explained.

A grooved disk 4, keyed upon the main or driving shaft 1 that revolves in the direction indicated by the arrow shown in Fig. 2 and 50 that is journaled in the lower part of the machine-frame 2, 3, is engaged by the roller 5 mounted on a lever 7, which is fulcrumed at one end, as is shown at 6, and the other end of which is connected, by means of a

link-rod 8, with one arm 9 of a bell-crank 55 lever, of which the other arm is indicated by 10. This bell-crank lever is mounted fast on the shaft 11, which is journaled in the upper part 3 of the machine-frame. To the arm 10 of the bell-crank lever, there is pivotally 60 connected one end of a link 12, the other end of which is coupled, in a manner that will be explained hereinafter, with two toothed racks 13, 14, arranged parallel to and at a distance from each other. The racks 13, 14, 65 are longitudinally slidable in grooves formed in the supports 15, 16 and rollers 17 (Figs. 1 and 6). Either of the racks 13, 14, may be moved, by means of the link 12, to and fro for the same distance and to such an extent 70 that pinions meshing with the racks 13, 14, will be revolved half a turn in either one or the other of two opposite directions. The rack 13 meshes with six pinions marked 18 and with two pinions 19, 21, having equal 75 diameters. All these pinions just named rotate idly, and are mounted free to slide axially, upon the shafts 24^a, 24^b, 24^c, 24^d, 24^e, 24^f, 24^g, 24^h, respectively, which are arranged crosswise and parallel to one another 80 in the bearings 22, 23, and perpendicular to and above each of the racks 13, 14. Each of the shafts just named is provided with a crank.

From a lateral face of each pinion 18, 85 there extends laterally an elongated hub in which there is formed an annular groove in which engages a slide 25 that is mounted on the lower end of the downwardly-projecting arm 26 of a bell-crank lever, the other arm of which is marked 26' (Fig. 11). The end-face of each elongated hub carries a dog or catch 27 (Fig. 12) and the opposite face of the pinion 18 is provided with a dog or catch 28 (Figs. 11 and 12), which 90 is in exact axial alinement with the dog 27. Both the catches 27, 28, have the form of quadrant-shaped segments (Figs. 2 and 12) and engage and serve as carriers for the collars or sleeves 29, 30, respectively, 95 which are fast on the shaft on which the pinion 18 is idly mounted. These sleeves 29, 30, are formed with dogs or teeth 29^x, 30^x, respectively, which, like their co-acting catches 27, 28, are quadrant-shaped segments (Fig. 12). The tooth 29^x is displaced from the tooth 30^x by an angle of 100 one hundred and eighty degrees (180°). 105

Let it be assumed that the pinion 18 is so adjusted, on its shaft, that its dog or catch 27 lies in advance of or underneath the tooth or dog 29^x of the sleeve 29 (see I, Fig. 12); it is obvious that the shaft will not be rotated, if the pinion 18 be given half a turn clockwise. If, however, owing to the operation of a perforated pattern-strip acting in a manner that will be explained hereinafter, the pinion 18 is shifted axially along the shaft, until the dog 28 of the pinion 18 is thrown into engagement with the dog 30^x fast on the sleeve 30, the latter dog being in advance of the dog 28, the sleeve 30 and its shaft will be carried through an angular displacement of one hundred and eighty degrees (180°) by giving the pinion half a turn clockwise (or in the direction of the arrow in Fig. 12) and will assume the working position marked II in Fig. 12. During the idle movement of the rack 13 (Figs. 1, 2), the dog 28 is rotated half a turn counter-clockwise and the shaft is left in its working position, in which the crank points downwards (see III, Fig. 12). If the pinion 18 be shifted again axially along the shaft, but in an opposite direction, the dog 27 will engage with the dog 29^x, as is illustrated at IV, Fig. 12, while the dog 28 will become disengaged from the dog 30^x and will assume a position alongside the latter. At the next working rotation of the pinion 18 in the direction of the arrow shown in Fig. 12, the dog or tooth 27 of the pinion 18 will engage the dog 29^x of the collar or sleeve 29, and the shaft on which the collar and the pinion are mounted will consequently be turned and the crank of that shaft will again assume its upright position (see I, Fig. 12).

Each of the cranks of the shafts 24^a, 24^b, 24^c, 24^d, 24^e, 24^f, 24^g, 24^h, is, by a link 31, connected to an end of one of the two-armed double-levers 32, 33, 34, 35, 36, respectively (Figs. 1, 2, 5). The levers 32, 35, have arms of equal length, while the lengths of the arms of the other levers 33, 34, 36, are in the ratio of 1:2. By means of pivot-pins, the levers 32, 35, are fulcrumed, at their mid-points, on the free ends of the longer arms of the levers 33, 34, respectively. The latter levers 33, 34, are fulcrumed on pivot-pins carried by the free ends of two parallel levers 38, which lie adjacent to but spaced from each other (Fig. 1) and are mounted fast upon the same fulcrum-shaft or common axis 37. The arrangement of the levers 32 and 35 and of the levers 33 and 34 is symmetrical with regard to the shaft 37. This fulcrum-shaft 37 is journaled between the adjacently-lying free ends of the longer arms of a pair of two-armed levers 39, the ratio of the lengths of the arms of which is as one is to

two. Lever 36 is fulcrumed between the adjacently-lying free ends of the shorter arms of these two-armed levers 39, the fulcrum-shaft or axis of which is marked 40. Pivoted on the trunnion or shaft 40 is a rack 41, which will be called hereinafter the driving rack in order to distinguish the same from a rack 42 pivoted on the fulcrum or shaft 37. The rack 42 serves to ensure a positive connection between the frame and the cranks, when the rack 41 is out of engagement with the gear 43. In order to cause the frame to be shifted, the driving rack 41 is positively connected with or geared to a horizontal rack 44 by means of a gear 43 of double width (Figs. 1, 2, 4), which meshes with both racks 41, 44, and which is connected, in a manner not shown, with the frame of an embroidery machine. With the rack 44, there also meshes a pinion 45 mounted co-axially and connected with a pinion 46, which is located, closely adjacent to the rack 44, in the same vertical plane as the rack 42. The diameters of the pinions 45, 46, are in the same ratio to each other as the lengths of the arms of the two-armed levers 39, to-wit, as one is to two. The pitch of the rack 44 corresponds exactly to an assumed displacement of the frame by the crank of the shaft 24^g of, say, five millimeters. The crank of the shaft 24^g is, at points in the description that follows hereinafter, referred to as the five-millimeter crank. These five millimeters represent, in the working example shown, a unit for the shifting movement of the frame. The throws of the cranks of the six shafts 24^a, 24^b, 24^c, 24^d, 24^e, 24^f, as regards the lengths of their arms or lifts, are, respectively, in such a ratio to the throw of the crank of the shaft 24^g, that they will produce, by means of the respective transmitting levers, displacements of the frame amounting to one sixtieth or to a number of or several sixtieths of the unit just mentioned. For example, let it be supposed that the distance between the dead-point positions of the crank of the shaft 24^a be 6 millimeters; of the crank of the shaft 24^b be 3 millimeters; of the crank of the shaft 24^c be 22.5 millimeters; of the crank of the shaft 24^d be 11.25 millimeters; of the crank of the shaft 24^e be 24 millimeters; of the crank of the shaft 24^f be 12 millimeters; and of the cranks of the shafts 24^g, 24^h, be each 22.5 millimeters. If, for instance, the shaft 24^b be actuated, that is, positioned or adjusted, the three millimeters will be transmitted to the end of the lever 32 that is connected therewith, which lever will turn about its other end; and, inasmuch as the lever 33 is engaged at the middle of the lever 32, lever 33 will, pivoting on its end that is connected with the shaft 24^c, turn through or half this

distance, that is, for one and one-half millimeters. Inasmuch as the lever 38, turning about its end that is connected with the lever 34, engages or is pivotally connected with the lever 33 at a point one third of the length of the latter therealong, the one and one-half millimeters turned by the lever 33 will be reduced by two thirds, that is, to one half of a millimeter, which, reduced to one half thereof (or a quarter of a millimeter), will be transmitted by the lever 38 to the lever 39. This one fourth of a millimeter, reduced by two thirds thereof, will be transmitted to the rack 41, resulting thereby in an effective lift of the frame of 0.08333 millimeter, which is one sixtieth of five millimeters, or one twelfth of one millimeter. The throw of the crank of the shaft 24^a produces a lift amounting to two sixtieths of the unit, or to two twelfths (or one sixth) of a millimeter; that of the crank of the shaft 24^c effects a lift amounting to thirty sixtieths of the unit or to thirty twelfths (or two and one half) millimeters; that of the crank of the shaft 24^d results in a lift of fifteen sixtieths of the unit or to fifteen twelfths (or one and one quarter) millimeters; that of the crank of the shaft 24^e is transmitted as a lift of eight sixtieths of the unit or eight twelfths (or two thirds) of a millimeter; and finally, that of the shaft 24^f produces a lift of four sixtieths of the unit or four twelfths (or one third) of a millimeter. In the aggregate, therefore, the throws of the cranks of the six shafts 24^a, 24^b, 24^c, 24^d, 24^e, 24^f, effect a lift of sixty sixtieths of the unit or sixty twelfths (or five) millimeters; and this distance, as hereinbefore set out, is the displacement of the frame due to the throw of the crank of the shaft 24^g. Within these limits, there will be afforded, due to the throws of the cranks of the shafts 24^a, 24^b, 24^c, 24^d, 24^e, 24^f, the possibility of shifting the frame any desired number of these sixtieths of the unit. If, for example, the frame is to be given a horizontal displacement of forty-eight sixtieths of the unit, the throw of the crank of each of the shafts 24^c, 24^d, 24^b, 24^a, will have to be adjusted for this extent of displacement in a manner to be hereinafter explained.

It results from the foregoing that the extents of the lifts due to the throws of the adjusted cranks will be added up on the levers 39, which may easily be gathered from the following reasoning: If the cranks of both shafts 24^a, 24^b, are set in a downwardly-pointing position, their strokes or throws will be transmitted simultaneously to the lever 33, as both ends of the lever 32, will be displaced downwards due to the strokes or throws of the cranks connected therewith. If the throw of the crank of the shaft 24^c has also been adjusted at the

same time, the fulcrum of the lever 33 will also be displaced downwardly due to the stroke of this crank. The stroke of the crank of the shaft 24^h produces a displacement of the frame amounting to two units 70 or ten millimeters, and, at points in the following description, this crank is designated as the ten-millimeter crank; therefore, with the effects of all the cranks taken together, a displacement of the frame amounting to 75 four whole units will be possible; thus, the throws or strokes of the cranks of the six shafts 24^a, 24^b, 24^c, 24^d, 24^e, 24^f, will produce a lift of one unit, the throw of the five-millimeter crank of the shaft 24^g will 80 effect a lift of another unit, and the stroke of the ten-millimeter crank of the shaft 24^h will result in a further lift of two units. This method of shifting the frame offers various advantages, namely, the adjustment 85 of the frame will be the most exact one conceivable owing to the multiple transmission of the strokes of the cranks, the wear of the cranks cannot have an appreciable influence on the precision of the adjustment 90 of the frame, which may be divided up in any number of sub-parts of or with regard to a given unit, and the use of brakes is not needed; moreover, the performance of the work by the controlling mechanism is 95 nearly noiseless.

The changing of stitches, in other words, the determining of the direction of the displacement of the frame (if, in a horizontal direction, whether to the left or to the right, 100 or, if in a vertical direction, whether upwards or downwards), will be effected by an apparatus hereinafter described, which apparatus can act on only the two crank shafts 24^g, 24^h. Between these two shafts, 105 a sleeve 48 is idly mounted and is slidable lengthwise on a stationary shaft 47 arranged parallel to the same. This sleeve carries two pinions 20, 20' (Figs. 1 and 15) spaced, or set at a distance from each other and of 110 equal diameter, and two shoulder-rings 49, 50, of which ring 49 may be engaged simultaneously with the indentations provided at the periphery of two stitch-changing-disks 51, 52, located in the same vertical plane 115 with the ring, while ring 50 may be engaged with the indentations of two reversing disks 53, 54. The disks 51, 52, 53, 54, have each two indentations 55 diametrically opposite each other (Fig. 8), which, while these disks 120 are at rest, are located in a horizontal plane passing through their axes. These indentations 55 are intended to prevent, by co-operating with the shoulder-rings 49, 50, turning of either the two stitch-changing 125 disks 51, 52 or the two reversing disks 53, 54. The stitch-changing disk 51 and the reversing-disk 53 are loose on the crank-shaft 24^g, while the disks 52 and 54 are loose on the crank-shaft 24^h. On their op- 130

posed lateral faces, the stitch-changing disks and the reversing disks are provided with or carry pinions, whereby and through which either the stitch-changing disks or the reversing disks may be engaged with the small pinion 20'. The distance of the pinion 20' from the shoulder-rings 49, 50 is chosen so that the shoulder-ring 49 secures the stitch-changing disks against turning, when the pinion 20' meshes with the pinions of the reversing disks 53, (54; while the latter are stopped by the ring 50, when the pinion 20' meshes with the pinions of the stitch-changing disks 51, 52. The axial displacement of the sleeve 48 is effected, in exactly the same manner as is the shifting of the pinions 18, by means of a bell-crank lever 56, which engages in an annular groove and is controlled, as will be explained later on, by the perforated pattern strip. On their external side-faces, the stitch-changing disks and the reversing disks are each provided with a pawl 61, 62, 63, 64, which is yieldingly pressed against the periphery of a carrier-cam 57, 58, 59, 60. The carrier-cams 57, 58, are fast on the shaft 24^g; while the carrier-cams 59, 60, are fast on the shaft 24^h and are displaced from each other by an angle of 180°. In the initial position of the stitch-changing disks and of the corresponding reversing-disks, the pawls 61, 62 (or the pawls 63, 64) are in alignment in an axial direction. Each of the shafts 24^g, 24^h, carries, besides the carrier-cams 57, 59, a fixed ring 65, 66 (Figs. 1, 15). These rings 65, 66 are formed, on their sides that face the pinions 19, 21, respectively, with bevelled or sloping clutch jaws or teeth with which the similar or corresponding jaws or teeth 67, 68, respectively, of the pinions 19, 21, may become engaged or disengaged, when the latter are shifted axially by means of the bell-crank levers 69, 70, respectively, from one end-position to the other. The adjustment or positioning of each of the pinions 18, 19, 20, 21, is effected as already described, by a bell-crank lever. All these bell-crank levers are idly mounted free to turn on a common shaft 71 which is located above and parallel with the rack 13 and engage, by means of their downwardly-extending arms and the slides 25, with the annular grooves formed in the lengthened hubs of the pinions. Each of the other laterally-extending arms carries, at its free end, a rotatable eye-bolt 72, into the eye of which is inserted the upper end of a rod 73, 74, 75, 76, 77, 78, 79, 80, 81, respectively, (Figs. 1 and 2). The lower ends of the latter rods are hingedly connected with the laterally-projecting arms of the bell-crank levers 82, 83, 84, 85, 86, 87, 88, 89, 90, respectively, the hubs of which are tubular and are each loosely mounted on a stationary horizontal shaft, and the downwardly-projecting arms of which are displaced laterally with respect to one another, as may be seen from an inspection of the upper half of Fig. 1. With each of these downwardly-projecting arms there is connected a horizontal push-rod 91, 92, 93, 94, 95, 96, 97, 98, 99, respectively. These connecting push-rods lie close to and alongside one another and are attached at their forward ends (Figs. 1, 2, 10) to the ends of the arms of two-armed levers 100. These levers 100 are all mounted loosely and rotatably on a common shaft 102. The lever 101 (Fig. 11) is, however, fast on the latter shaft, which carries also a lever 103 rigidly connected therewith. On the ends of the arms of the levers 100, 101, are pivotally-mounted two platines 104, 105, free to swing up, and down, on pins, and provided with hooks at their free opposed ends, with which a horizontally slidable double knife 106 of a T shaped cross-section cooperates. The corresponding platines (that is to say, the platines carried by the same lever 100) are connected with a common touching needle 107, which is slidable in a vertical direction. These platines lie in or fit into a suitable notch of the needle, so as to swing upwardly and downwardly together with the up-strokes and the down-strokes of the needle whereby at the same time, with their hooks, one moves out of while another comes within the reach of the knife 106. If this knife is moved from the dotted-line position, of Fig. 10 into the full-line position, it will, in the first part of its travel or stroke, carry along with it the platines that are within its reach and will throw the levers 100, 101, connected therewith, in a corresponding direction. The turning of these levers 100, 101, being as a matter of fact a positive movement, and one avoiding the use of springs, will be transmitted through rods 91, 92, 93, 94, 95, 96, 97, 98, 99, levers 82, 83, 84, 85, 86, 87, 88, 89, 90, rods, 73, 74, 75, 76, 77, 78, 79, 80, 81, and levers 26, 26', 56, 69, 70, to the pinions 18, 19, 20, 21, which will thereby be moved from one end-position to the other. Each touching-needle 107 is controlled by a spring 108, which bears, at its lower end, against a guide-plate 109, and, at its upper end, against a horizontally-disposed pin 110 having both its ends projecting from the sides of the needle; whereby the upward travel or throw of the needle is produced. In order to prevent the needle from turning, one end of the pin 110 extends laterally towards a cross-bar 111 and into a vertical guide-slot formed in a plate 112 mounted fast on the bar 111. The touching-needles are reduced or taper, at their upper ends, into needle-points which glide over the periphery of a jacquard roller 113 provided, in a manner well-known in connection with jacquard

rollers, with rows of holes which cross one another. Around the jacquard roller 113, the pattern-strip 114 is laid. The step-by-step movement of the jacquard roller is produced, in a well-known manner, as by means of a ratchet-wheel 115 rotated by the movable pawl 116, (Fig. 2), the lever 117 carrying which pawl is attached by means of a link-rod 118 to the swinging arm 119 provided with a friction-roller 120 that bears against a cam-disk or eccentric 121 keyed to the main-shaft 1. The arm 119 is swung up and down alternately, by the rotation of the cam-disk 121. The jacquard roller 113 is held locked, during the downward swing, against accidental displacement, by means of a tilting-pawl 122 the toe-end of which engages the teeth 123 of a toothed wheel (Figs. 2, 6). The ends of the knife 106 travel in sideways or guides 124 (Fig. 10); and the knife is actuated, by means of a multiple-armed lever 125 mounted idly and rotatably on the shaft 11. The tubular hub of the lever 125 is provided with an arm 127 connected, by means of a link 128, with a swinging arm 129 (Fig. 2), provided with a cam-roller 130, which travels in the cam-groove 131 formed in a cam-disk 132 keyed to the main shaft 1. By this arrangement of parts, the pivoted arm 129 is swung up and down. The hub of arm 125 is, in addition, provided with an upwardly-projecting cam-segment 133 (Fig. 9) against the irregular cam-surface of which rubs a cam-roller mounted on one arm of a two-armed lever 135 keyed fast to shaft 134. This lever 135 carries mounted upon its other arm, one end of a bar or plate 136 the other end of which is connected with a lever 135' fast on the shaft 134. The longitudinal edge of the plate 136 which is deflected from the shaft 134 engages the pins 110 of the touching needles 107 (Fig. 9). The latter will, therefore, be moved simultaneously downwards and the points will thereby be withdrawn from the holes of the jacquard roller 113 and of the pattern strip 114, when plate 136 is moved or swung downwards, which will be effected during the back stroke 50 of the knife 106, by means of the forward swinging of the cam-segment 133 and the resulting upward travel or movement of the arm 135 bearing thereagainst on the part thereof having an increased radius.

In order to adjust the crank-shaft 24^g, 24^h, so that the stitch-changing may occur before the working stroke of the rack 13 (Figs. 1 and 2), that is, during the idle stroke of the same when moving into the position required for the next stitch, the point of the touching-needle connected with the sleeve 48 is bent backwards so as to be in advance, with respect to the other needles, by the amount of one cross-row of holes in the pattern strip with regard to its engagement therewith. Moreover, the arrangement of the lever 89 is reversed on its axis with regard to the levers 82 to 88 and 90 (Figs. 1 and 2), which will cause the horizontal arm of the lever 89 not to swing downwards at 70 the forward-stroke of the knife 106, but to swing upwards and will thereby cause the reversing of the sleeve 48 from its full-line position shown in Fig. 15 to its dotted-line position therein, while, at the same time, 75 the reversing of the pinions 18 into their initial position, that is, from the dotted-line position shown in Fig. 12 to the full-line position shown therein, will take place. If, for instance, no hole should have been provided, within the pattern strip, for the stitch-changing device, the cranks of the shafts 24^g, 24^h, would always work from above downwards and, they work inversely (that is, from below upwards), only in case 80 of or connection with the stitch-changing. After each stitch produced with the aid of one of these cranks (that is after a stitch of at least the size of a unit), the stitch-changing device will for the next idle stroke 85 of the rack (backwards) cause the cranks to be brought again into their starting position, pointing upwards; and, inversely, is the case if a hole has for the stitch-changing, been provided in the pattern strip, for then 90 the cranks will temporarily be turned downwards, during the idle stroke of the rack.

The foregoing will be more clearly explained with reference to the freely arbitrarily-chosen hole-diagram of the pattern-strip shown in Fig. 29 and with reference 100 to the Figs. 15 to 28.

In Figs. 16 to 28, the rack 13 is indicated by only a line, and the pinion 20, which meshes therewith, is shown as being of a 105 larger size than the pinion 20'.

The reversing disk 53 is represented, for the sake of clearness and convenience, as being below the stitch-changing disk 51. In each figure, the illustrated position of the 110 crank is that taken by it at the end of the movement of the rack in the direction of the arrow. As the operation of the five-millimeter and ten-millimeter cranks is exactly the same, the ten millimeter cranks 115 have been omitted for simplification and clearness. The first row of holes on the left of the pattern diagram relates to the five-millimeter cranks, the second row to the stitch-changing. If a hole has been provided in only the first row, the five millimeter crank concerned will work from above downwards; if, however, there is a stitch-changing hole besides the hole designed for the five-millimeter crank, the latter will work from below upwards.

1st stitch.—The initial position of the stitch-changing device is shown in Figs. 15 and 16. The crank points upwards and the two pawls 61, 62 likewise, the shoulder on 130

the cam 57 that co-acts with the pawl 61 is down and the shoulder on the cam 58 that co-operates with the pawl 62 is up. As, for the first stitch, there is a hole for the five-millimeter crank in the pattern-strip, the pinion 19, by means of the tooth or dog 67, will be engaged with the tooth 65 provided on the crank-shaft 24^g. At the forward stroke of the rack 13, the five-millimeter 10 crank of the shaft 24^g will turn clockwise for half a revolution, that is, it will move from its upper dead-point position into its lower one (Figs. 16 and 17). As, for the next 15 stitch, there has been provided, for the stitch-changing device, a hole in the pattern strip, and, as the touching-needle is one step in advance of the jacquard-roller, the stitch-changing disk 51, which is driven by the pinions 20, 20', will, at the same time and 20 at the forward-stroke of the rack, make half a turn counter-clockwise. The stitch-changing disk and the crank-shaft 24^g will therefore turn simultaneously in directions opposite to each other. At the back-stroke of the 25 rack, the stitch-changing disk will make an idle half-turn clockwise. The crank will therefore remain pointing downwards (Fig. 18).

2nd stitch.—For the five-millimeter crank 30 of the crank-shaft 24^g, there is provided a hole, in the strip; therefore, the jaw 67 will engage with the jaw 65. At the forward stroke of the rack, the crank will, therefore, rotate through half a turn from its lower 35 into its upper dead-point position. As there is no stitch-changing hole for the next stitch, the pinion 20' is engaged with the reversing disk 53. This latter disk will, therefore, make half a revolution counter-clockwise, during the forward-stroke of the rack (Fig. 40 19). The pinion 20' remains engaged with the reversing disk 53. At the backward-stroke of the rack, the reversing disk 53 will 45 make an idle half-turn clockwise and the crank will remain pointing upwards (Fig. 20).

3rd and 4th stitches.—At the forward-stroke of the rack, the five-millimeter crank 50 swings downwardly, the jaw 67 engaging with the jaw 65. The reversing disk 53 turns for half a revolution counter-clockwise, bringing the pawl 62 behind the tooth of the cam 58 (Fig. 21). At the back-stroke of the rack, the pawl 62 will push the cam 58 55 along with it and will turn the crank so that it will point upwards (Fig. 22).

5th stitch.—As there is no hole provided in the pattern-strip for the five-millimeter crank, the tooth 67 will not be engaged with 60 the tooth 65 and, at the forward stroke of the rack, the crank will, therefore, remain in its upper dead-point position. The reversing disk 53, driven by the pinion 20', will make an idle turn counter-clockwise 65 (Fig. 23). At the back-stroke of the rack,

the disk 53 will turn again in the opposite direction, without the cam 58, and the crank will therefore remain pointing upwards.

6th stitch.—For the five-millimeter crank, 70 there is again no hole in the pattern-strip. The tooth 67 remains, therefore, out of engagement. But the sleeve 48 will be displaced by means of the advanced touching-needle of the stitch-changing device for the seventh stitch and thereby the pinion 20' 75 will be caused to engage with the stitch-changing disk 51 (Fig. 25). At the forward-stroke of the rack 13, the crank will remain pointing upwards; at the next following back-stroke of rack 13, however, the 80 crank will be turned so as to point downwardly, by the pawl 61 and the tooth of the cam 57, for the seventh stitch (Fig. 26).

7th stitch.—This stitch shows, in the pattern-strip, a hole for the five-millimeter 85 crank, wherefore the jaw 67 will again be brought into engagement with the jaw 65, so as to turn the crank upwardly at the forward-stroke of the rack. With this movement, the stitch-changing disk 51 will make, 90 with the pawl 61, half a turn to the left (Fig. 27), whereby the pawl 61 is brought so as to lie behind the tooth of the cam 57. At the back-stroke of the rack, the pinion 20' 95 will remain engaged with the stitch-changing disk 51, because, for the next stitch, there is again a hole for the stitch-changing; and the crank will be brought back again downwardly into its initial position for the stitch-changing.

8th stitch.—For this stitch, the same conditions exist as for the second stitch (compare Figs. 28 and 17). The eighth stitch is, therefore, produced in the same manner as the second.

The execution of certain and of all special operations, such as perforating, stippling, and the like, is caused by the same touching-needles as are employed for controlling or effecting the operation of the 110 cranks of the shafts 24^a to 24^f. Therefore, with the exception of one, no special longitudinal rows of holes are provided in the pattern-strip; but the holes that serve to control these operations, are located in the 115 same row, as are the holes for the adjusting of the stitches in sixtieths.

With each lug or tooth 28 of the pinions 18, there is engaged one end of a bar or rod 137, (Figs. 1, 12, 13), the other end of which carries or is attached to a slide-block 138 adapted to move within the annular groove 139, formed in the hub of a pinion 140^a, 140^b, 140^c, 140^d, 140^e, 140^f. Of these pinions, the ones marked 140^a, 140^b, 140^c, are mounted directly on the crank-shafts 24^a, 24^b, 24^c, 120 respectively, while the pinions marked 140^d, 140^e, 140^f, are mounted loosely and rotatably, and are slidable in an axial direction, 125 on short hollow shafts 141^d, 141^e, 141^f, re- 130

spectively. The latter shafts surround the shafts 24^a, 24^b, 24^c. Each of these pinions marked 140^a to 140^c mesh with the rack 14 and will, when the rack is moved to and fro, be rotated for half a turn clockwise or counter-clockwise (Fig. 2). The pinions 140^a, 140^b, 140^c, (see Figs. 1 and 13) are provided on the outer side face of each with two teeth 142 arranged to engage with two teeth 143 provided on the short shaft 144, which receives one end of shaft 24^a, or (as the case may be) of shaft 24^b or shaft 24^c, and which is fitted, outside of the bearing 22, with a crank 145 (not shown in Figs. 1 and 2), the position of rest of these cranks being marked I in Fig. 13, and the working-position thereof being marked II therein. The manner of connecting these cranks with the driving mechanism for the special operations of the embroidery machine is not illustrated. The gear wheels marked 140^a to 140^c are shaped in a manner similar to the pinions 18; the hub of each of the pinions 140^a, 140^b, 140^c is provided with an annular groove and with a lug 146, and, on the side face looking downward in Figs. 1 and 14, with a lug 147. The first-named lug co-acts with a lug 148 formed on the short hollow shaft 141^a, 141^b, 141^c, respectively, and the lug 147 with lug 149 set at an angle of 180°, relatively to lug 148. The axial displacement of the pinions 140^a, 140^b, 140^c, is effected in exactly the same manner as is the displacement of the pinions 140^a, 140^b, 140^c from the pinions 18 mounted co-axially or on the same shaft. Moreover, the mode of operation on the hollow shafts 141^a, 141^b, 141^c is exactly the same as it is with the pinions 18 on their corresponding crank shafts, wherefore, for this arrangement also, the illustrations given in Fig. 12 will be applicable. The cranks 150 of the hollow shafts 141^a, 141^b, 141^c, serve to control the perforating mechanism of the embroidery machine. They are of unequal length and are each connected with the upper end of a link 151 (Fig. 3). The two links on the left engage, with their lower ends, the ends of the common lever 152 (Fig. 3). To the middle portion of this lever, there is connected pivotally one end of a lever 153, the other end of which is hingedly connected to the link 151 on the right of Fig. 3. The lever 153 is attached to a rod 154, which is adapted to be connected with the perforating apparatus of the embroidering machine. This mode of connecting the control device with the perforating apparatus will afford the possibility of adjusting the perforating apparatus in seven different positions, each by means of a single adjustment, or revolution of the machine.

In order to have the cranks of the shafts 24^a to 24^b, 144, and 141^a to 141^c maintained rigidly fast in the upper position, or in the

lower position, as the case may be, if some of these parts should be turning with respect to any part at rest, each of the shafts just named is provided with a circular disk 155 (Fig. 7) having, in its periphery and in the axial plane of the crank, two curved or bow-shaped recesses 156, each of which is adapted to be engaged by a roller 157 bearing against the periphery of the disk and mounted on the end of a lens 159 75 pressed downwardly by a spring 158.

The change or reversal from working with the rack 13 to working with the rack 14, and inversely, is effected by means of two bolts 160, 161 which are spaced from each other 70 and arranged coaxially, as is illustrated for the rear end-position of these racks, in Figs. 10 and 11. The bolts 160, 161, are mounted in the bores of eyes formed in the racks 13, 14, and are slidable therein in an axial direction. From each bolt, a pin 162, 163, projects outwardly through a slot 164 formed in the wall of the bore or eye of the corresponding rack. The length of the bolts and their distance from each other are so 80 taken, that, for instance, for the operation of rack 14 (Fig. 11), one end of the bolt 160 will be completely withdrawn from the bore of the link 12 and its opposite end will extend out of the eye of the rack 13 and will 90 become engaged in the eye formed in the arm 165 that projects upwardly from a stationary horizontal shaft 166, thus securing the rack 13 against any accidental displacement in a longitudinal direction. One end 95 of the bolt 161, however, extends to the middle portion of a hole formed in the link 12 and its other end is withdrawn from the hole formed in an arm 167 projecting upwardly from the shaft 166. The bolt 161 serves, 100 therefore, as a carrier or coupler between the link 12 and the rack 14, when the link 12 is moved by the main shaft in the manner hereinbefore described. All these conditions are reversed, if the rack 13 is to be moved by 105 the link 12 through the medium of the bolt 160. The bolt 161 is then withdrawn from the link 12 and projects into the middle of the hole formed in the arm 167. On the other hand, the bolt 160 is withdrawn from 110 the hole formed in the arm 165 and projects into the hole formed in the link 12. In the reversed position of the racks, which is assumed by them in the rear end-position of the latter, the lower ends of the pins 162, 163, 115 engage in the open slots 168, 169, of a lengthwise-displaceable slide 170 mounted on the shaft 166. If this slide is displaced to the right from the position shown in Fig. 11, so as to bear against the arm 167, the two bolts 120 160, 161, will be carried along by the two pins 162, 163 to their other end position, and the bolt 160 will enter the hole formed in the link 12, before the bolt 161 leaves the same. The to-and-fro movement of the slide 170 125

is produced by the following arrangement of parts, to-wit: To the slide 170, there is pivotally connected one end of a link-rod 171 the other end of which is hingedly fastened 5 to the free end of an arm of the bell-crank lever 172. To the free end of the other arm of the latter, there is pivotally fastened the upper end of a connecting-rod 173 the lower end of which is similarly fastened to the 10 rocker-arm 103 mounted fast on the rock-shaft 102. Upon the shaft 102, there is also mounted fast (as has hereinbefore been described) the rocker-arm or lever 101, which co-acts with the outer touching-needle 15 shown on the left of Fig. 6. If this touching-needle sinks into a hole of the pattern-strip, the lower platine 104 will, at the next working stroke of the knife pull on the lower end of the lever 101, and will thereby 20 turn the shaft 102, so as to swing the arm 103 thereof downwards, which will, by means of the parts 173, 172, 171, 170, and the pins 162, 163, push the bolts 160, 161, into that 25 end position in which the rack 14 is stopped and the rack 13 is coupled with the link 12. Should there be no hole provided in the pattern strip for the touching-needle, the reversing device will assume the position illustrated in Fig. 11, in which the rack 14 is 30 shown coupled with the link 12.

In Fig. 4, the manner in which the racks 41, 42, are alternately thrown into and out of gear is diagrammatically shown, in other words, the manner of alternately stopping 35 and permitting the movement of the frame. Each of the racks 41, 42, is shaped like a frame, in which a slide-block 174, 175 is provided. The slide-block 174 is fitted to one end of a bell-crank lever 177 fulcrumed 40 at 176 and swung to and fro by means of a cam-disk or eccentric 178 mounted on the main shaft 1. By these means, the rack 42 is swung to and fro and is thereby thrown into and out of gear with the pinion 46. 45 The slide-block 175 is similarly moved by means of a cam-disk 182, which is mounted on the main shaft 1 and against which bears one end of a rod 181, the other end of 50 which is pivotally connected to a lever 180 fulcrumed at 179. The cam-disk 182 is in such a position with respect to the cam-disk 178 that the latter is in advance of the former by about 90°. The curves of the two 55 main shaft revolves in the direction indicated by the arrow in Fig. 4, the rack 41 will be thrown into mesh with the pinion 43, shortly before the rack 42 is thrown out of mesh with the pinion 46, and that, later 60 on, the rack 42 will be thrown again into mesh with the pinion 46 shortly before the rack 41 is thrown out of mesh with the pinion 43. Resulting from (1) the engagement 65 of the rack 42 with pin 37, (2) the employment of the transmission gears 45,

46, and (3) a pitch corresponding to the unit of the displacement of the frame, a displacement of the rack 44 for more than a unit (that is, for an integral number thereof) will be compensated, so that the 70 rack 42, after each displacement of the frame, will again mesh with the pinion 46. In order to simplify the drawings, cam-disks have been shown, but, in practice, grooved disks would preferably be used, so 75 that the throwing into and out of gear of the racks 41, 42 would be affected in a positive manner.

In the foregoing, only one half of the automatic mechanism has been described, the other half in Fig. 1 shown as the upper one, is exactly alike, that is, it is symmetrical with regard to the crank shafts, to the stitch-change mechanism and the control and operation thereof and with respect to a 80 vertical, longitudinal and central plane. The operation of the racks for the vertical displacement of the frame is similarly effected by the shaft 11 through the intermediary of the lever 10' mounted fast on that 85 shaft; the reversal of this rack gear is also effected by means of the shaft 102, and simultaneously with and in exactly the same manner, as in the operation of the 90 horizontal displacement of the frame. 95

The operation of the described automatic controlling mechanism in an uninterrupted or closed cycle during one revolution of the main shaft 1 may be described as follows: Such a revolution is assumed to be divided 100 into sixteenths. The initial position of the driving mechanism and of the knife is illustrated in Fig. 2, in which, during the stitching the rack 13, and, in the case of adjustment for the special operations, the rack 14 105 take their rear end-positions, and, furthermore, the knife 106 assumes its forward end-position. The whole working operation may for greater clearness be divided into two subordinate or component operations, 110 to-wit: First, the operation of the parts concerned in the movement of the frame; and second, the reversing or, as the case may be, the control of the same, by means 115 of the pattern strip.

1. During the first four sixteenths of a revolution of the main shaft, the forward stroke of the rack 13 (or 14) takes place and thereby the feed of the frame or the throwing into or out of gear of the mechanisms concerned in special operations, such as perforating and so on. During the fifth sixteenth of a revolution, the throwing into gear of the frame-stopping racks 42 and 46, 120 will occur. From the sixth sixteenth to the eighth sixteenth, the rack 41 is thrown out of gear, then the back strokes of racks 13, 14, occur, when (if it may), the operation of the stitch-change mechanism will take 125 place. From the thirteenth sixteenth to the 130

fifteenth sixteenth the throwing of the rack 41 into mesh with the gear 43 will be effected, while during the last sixteenth, the rack 42 will again be thrown out of mesh.

5 2. During the first three sixteenths, the knife remains motionless in its forward end-position. In the next two sixteenths (the fourth and the fifth), the back or reverse travel of the knife takes place. During the sixth and seventh sixteenths, the touching-needles will become disengaged or withdrawn. From the eighth to the tenth sixteenth, the feed of the jacquard roller 113 is effected. In the next two sixteenths, 15 the feeling of the touching-needles occurs. And, finally, during the remainder of the revolution, there occur the forward travel of the knife and, simultaneously therewith, the adjusting of the pinions, that is, the adjustment for the new stitch.

So far as the driving means or parts are concerned, the shaft 24^g is actuated in precisely the same way as is the shaft 24^h, which is particularly clearly illustrated in 25 and becomes apparent from an inspection of Figs. 1, 2, 8, 15, reference being had to the foregoing description. The pinions 19, 21, which are idly mounted on the crank-shafts 24^g, 24^h, respectively, mesh with the 30 toothed rack 13; and, when the latter is shifted back and forth, the pinions 19, 21, are caused to rotate in the same direction. If the pinion 19 is not interlocked with the 35 coupling-ring 65 and the pinion 21 is out of engagement with the coupling-ring 66, the rotation of the pinions 19, 21, is an idle one on their shafts 24^g, 24^h, and these shafts are not carried along with the pinions in their turning movement. But, if the 40 pinions 19, 21, are clutched to the coupling-rings 65, 66, respectively, the shafts 24^g, 24^h, will be caused, by the longitudinal displacement of the rack 13, to rotate at the same time and to the same extent and in the 45 same direction, that is to say, in a clockwise direction. Now it is obvious that both the crank-shafts 24^g, 24^h, need not rotate at the same time or remain motionless at the same time, for it may happen that only one 50 or the other thereof need be turned. The crank-shaft 24^g carries two cam-disks 57, 58, mounted fast thereon and spaced from each other; and the crank-shaft 24^h likewise carries two similarly mounted cam-disks 59, 60. The cams of the disks 57, 58, are set 180° apart, or one in advance of the other; and the cams of the disks 59, 60, are similarly positioned with respect to each other. On the crank-shaft 24^g, there are 55 idly mounted, between the cam-disks 57, 58, a stitch-changing disk 51 and a reversing-disk 53; and, between the cam-disks 59, 60, there are idly mounted, on the crank-shaft 24^h, a stitch-changing disk 52 and a reversing-disk 54. Each of these stitch-changing

disks 51, 52, and reversing-disks 53, 54, is provided, on its outer end-face, with a carrier-pawl 61, 62, 63, 64, which co-acts with one of the cam-disks 57, 58, 59, 60, and serves to turn the same in a clockwise direction, as illustrated in Figs. 1, 8, 15, and 16 to 28, both inclusive. The other lateral face of each of the disks 51, 52, 53, 54, is provided with a laterally-projecting, annular, toothed flange. As is shown in Fig. 75 15, the toothed flange of the disk 51 extends towards the toothed flange that projects from the opposite face of the reversing-disk 53; and the flanges of the disks 52, 54, are similarly arranged. On a stationary 20 shaft 47, arranged between the crank-shafts, there is mounted, free to be displaced axially along the shaft 47, a sleeve-shaft 48. Fixed upon the latter is a gear 20, which remains, during the lengthwise 25 shiftings of the sleeve-shaft 48, constantly in mesh with the toothed rack 13. (Fig. 15). Also fixedly mounted on the sleeve-shaft 48, there are two stop-rings 49, 50, and, between the same, a pinion 20'. This 30 pinion 20' meshes with either the toothed flanges of the two stitch-changing disks 51, 52, or those of the two reversing disks 53, 54. If the pinion 20' meshes with the two 35 stitch-changing disks 51, 52, through their toothed flanges, these disks 51, 52, will be rotated back and forth by the back-and-forth rotation of the sleeve-shaft 48 (upon 40 which the pinion 20' is mounted fast) due to the back-and-forth lengthwise displacements of the toothed rack 13 transmitted, through the pinion 20, to the sleeve-shaft 48. The direction of rotation of the disks 51, 52, will be the same, for the pinion 20' moves oppositely at the meshing points (or 45 points of engagement) with the disks 51, 52; and, since the driving points of the latter are displaced from each other 180° and therefore lie opposite to each other, it follows again that these stitch-changing 50 disks 51, 52, must likewise rotate in the same direction. Because the carrier-pawls 61, 63, lie in the same direction, with respect to the direction of rotation, they actuate the carrier-cams 57, 59, in the same direction and thereby drive the crank-shafts 24^g, 24^h, likewise in the same direction. When the pinion 20' meshes with the stitch-changing disks 51, 52, the reversing-disks 53, 54, are locked against rotation through 55 the engagement of the stop-ring 50 in the recesses 55 of these reversing-disks. Inversely, the stitch-changing disks will be held against rotation on the crank-shafts 24^g, 24^h, when the pinion 20' meshes with 60 the reversing-disks 53, 54, with respect to the propulsion of which the hereinbefore-described mode of operation of the actuating mechanism of the disks 51, 52, exactly applies. From the foregoing it is 65

clear that the driving of the crank-shaft 24¹ and its direction of rotation are exactly the same, both in its forward and reverse movements, as in the case of the crank-shaft 5 24².

Claims:

1. An automatic operating mechanism for embroidery machines, of the type in which the simultaneous vertical and horizontal dis- 10 placements of the frame which jointly determine the shifting thereof are, for each stitch, controlled by means of holes formed in a pattern-strip, said mechanism including a frame-actuating rack; a lever attached thereto; a series of cranks having different arm-lengths and adjustable, independently of one another in two positions opposite one to the other, each crank being capable of 15 producing a displacement of the rack cor- 20 responding to the throw of the crank; and a series of two-armed levers which connect the cranks with the first-named lever and transmit thereto the throws of the cranks.

2. An automatic operating mechanism for embroidery machines, of the type in which the simultaneous vertical and horizontal dis- 25 placements of the frame which jointly determine the shifting thereof are, for each stitch, controlled by means of holes formed in a pattern-strip, said mechanism including a rack; a lever attached thereto; a series of cranks having different arm-lengths and adjustable, independently of one another in two positions opposite one to the other, each crank being capable of 30 producing a displacement of the rack corresponding to the throw of the crank; a series of two-armed levers by which the first-named lever is connected to the cranks, and mechanism 35 for transmitting to the frame the aggregate of the throws of the cranks in substantially 40 reduced amount.

3. An automatic operating mechanism for embroidery machines, of the type in which the simultaneous vertical and horizontal dis- 45 placements of the frame which jointly determine the shifting thereof are, for each stitch, controlled by means of holes formed in a pattern-strip, said mechanism including a frame-actuating rack; a lever attached thereto; a series of cranks having different arm-lengths and adjustable, independently of one another in two positions opposite one to the other, each crank being capable of 50 producing a displacement of the rack corresponding to the throw of the crank; a series of two-armed levers which connect the cranks with the first-named lever and transmit thereto the throws of the cranks; 55 pinions for actuating the cranks; a pair of carriers for each of the pinions, said carriers cooperating therewith to rotate the cranks through a partial turn; a reciprocating rack common to the pinions for driving the 60 same; and a set of levers controlled by the 65

pattern-strip for displacing the pinions axially to such an extent that the pinion is brought within working reach of one of the pair of carriers that co-act with the pinion and rotate in the same direction as the latter 70 to bring the cranks into one or the other of their end-positions.

4. An automatic operating mechanism for embroidery machines, of the type in which the simultaneous vertical and horizontal dis- 75 placements of the frame which jointly determine the shifting thereof are, for each stitch, controlled by means of holes in a pattern-strip, said mechanism including a frame-actuating rack; a lever attached 80 thereto; a series of cranks having different arm-lengths and adjustable, independently of one another in two positions opposite one to the other, each crank being capable of 85 producing a displacement of the rack corresponding to the throw of the crank; a series of two-armed levers which connect the cranks with the first-named lever and transmit thereto the throws of the cranks; pinions for actuating the cranks; means for driving the pinions; a set of levers for effecting axial displacement of the pinions; touching needles cooperating with said set of levers; a plurality of pairs of platines; two-armed levers through the intermediary 90 of which and the platines said set of levers and the touching needles are connected; a reciprocating knife having a constant stroke and arranged to be engaged by the platines one of each pair of which is adapted to engage the knife from below while the other is adapted to engage the same from above, one platine coming within reach of the knife in one end-position of its respective touching-needle and the other platine coming 95 within reach of the knife in the other end-position of its touching-needle, the resulting displacement of the pinions in both 100 axial directions being positive.

5. An automatic operating mechanism for embroidery machines, of the type in which the simultaneous vertical and horizontal dis- 105 placements of the frame which jointly determine the shifting thereof are, for each stitch, controlled by means of holes formed in a pattern-strip, said mechanism including a frame-actuating rack; a lever attached thereto; a series of cranks having different arm-lengths and adjustable, independently 110 of one another, in two positions opposite one to the other, each crank being capable of producing a displacement of the rack corresponding to the throw of the crank; a series of two-armed levers which connect the cranks with the first-named lever and transmit thereto the throws of the cranks; a crank-shaft for each of the cranks; a plurality of pairs of pinions, each pair of which 115 pinions is mounted, side by side, on one of the crank-shafts and free to turn idly there- 120

on and is adapted to be connected with its respective crank; a ratchet-gear device for each of the crank-shafts, for actuating the same to bring the crank into one position 5 by means of one of the pairs of pinions and into an opposite position by means of the other of the pairs of pinions in order that, during the succeeding working stroke, the frame may be moved in one of two opposite 10 directions; a step-by-step feed roller; touching needles one of which engages the feed-roller in advance of the others; and an axially-displaceable train of gears common to a pair of the pinions for driving the lat- 15 ter and arranged to be axially displaced by the touching needle that preengages the feed-roller.

6. An automatic operating mechanism for embroidery machines, of the type in which 20 the simultaneous vertical and horizontal dis- placements of the frame which jointly de- termine the shifting thereof are, for each stitch, controlled by means of holes formed in a pattern-strip, said mechanism including 25 a frame-actuating rack; a lever attached thereto; a series of cranks having different arm-lengths and adjustable, independently of one another, in two positions opposite one to the other, each crank being capable of 30 producing a displacement of the rack cor- responding to the throw of the crank; a series of two-armed levers which connect the cranks with the first-named lever and trans- mit thereto the throws of the cranks; a 35 stitch-changing mechanism arranged to co- operate with a pair of cranks adjacent to each other and adapted to co-act with an end of the first-mentioned lever; and a pinion that is arranged between the last-named 40 cranks and that cooperates therewith.

7. An automatic operating mechanism for embroidery machines, of the type in which the simultaneous vertical and horizontal dis- placements of the frame which jointly de- 45 termine the shifting thereof are, for each stitch, controlled by means of holes formed in a pattern-strip, said mechanism including a frame-actuating rack; a pinion adapted to mesh therewith a two-armed lever attached 50 to the rack; a series of cranks having differ- ent arm-lengths and adjustable, independ- ently of one another in two positions oppo- site one to the other, each crank being capa- 55 ble of producing a displacement of the rack corresponding to the throw of the crank; a series of two-armed levers which connect the cranks with the first-named lever and trans- mit thereto the throws of the cranks, the arms of said first-named lever being of 60 unequal length; a second rack that is mounted at one end of said first-named lever and arranged to stop the frame, while the first-named rack is out of engagement; a transmission gear that includes a pinion 65 adapted to mesh with the second rack and

that corresponds to the ratio of the length of one of the arms of said first-named lever to the length of the other arm thereof and that is operated by the second rack; a third rack; a stitch-changing gear comprising pin- 70 ions that are in engagement with said third rack; and another rack positively connected with the frame and in mesh with the transmission gear and having a pitch cor- responding with the shortest stroke acting 75 on the frame and produced by one of the cranks that are connected with the stitch- changing gear and by one of the two racks first-named, which racks are adapted to be thrown into and out of mesh with their 80 respective pinions so as to throw one rack into gear before the other is thrown out of gear.

8. An automatic operating mechanism for embroidery machines, of the type in which 85 the simultaneous vertical and horizontal dis- placements of the frame which jointly de- termine the shifting thereof are, for each stitch, controlled by means of holes formed 90 in a pattern-strip, said mechanism including a frame-actuating rack; a lever attached thereto; crank-shafts; a series of cranks thereon having different arm-lengths and adjustable, independently of one another, in 95 two positions opposite one to the other, each crank being capable of producing a displace- ment of the rack corresponding to the throw of the crank; a series of two-armed levers which connect the cranks with the first- 100 named lever and transmit thereto the throws of the cranks; pinions for actuating the cranks; another pinion which is mounted on a crank-shaft and is axially displaceable thereon and is driven independently of the first-named pinions and is coupled there- 105 with in an axial direction; a hollow shaft arranged to be connected operatively with the embroidery machine and loosely mounted on the crank-shaft; and touching needles for controlling the pinions. 110

9. An automatic operating mechanism for embroidery machines, of the type in which the simultaneous horizontal and vertical dis- placements of the frame which jointly deter- 115 mine the shifting thereof are, for each stitch, controlled by means of holes formed in a pattern-strip, said mechanism includ- ing a frame-actuating rack; a lever attached thereto; crank-shaft; a series of cranks thereon having different arm-lengths and 120 adjustable, independently of one another in two positions opposite one to the other, each crank being capable of producing a dis- placement of the rack corresponding to the throw of the crank; a series of two-armed 125 levers which connect the cranks with the first-named lever and transmit thereto the throws of the cranks; pinions for actuating the cranks; second pinions mounted free to be displaced axially on part of the crank- 130

shafts and driven independently of the first-named pinions and coupled therewith in an axial direction; a second rack for actuating the second pinions; another rack for driving the first-named pinions that actuate the cranks; a driving member for reciprocating the two last-named racks; touching needles; and means controlled by one of the touching needles for causing said member to act upon either of said racks.

10. An automatic operating mechanism for embroidery machines, of the type in which the simultaneous vertical and horizontal displacements of the frame which jointly determine the shifting thereof are, for each stitch, controlled by means of holes formed in a pattern-strip, said mechanism including a rack; a frame-actuating lever; a series of cranks thereon having different arm-lengths and adjustable, independently of one another in two positions opposite one to the other, each crank being capable of producing a displacement of the rack corresponding to the throw of the crank; a series of two-armed levers which connect the cranks with the first-named lever and transmit thereto the throws of the cranks; pinions that are in mesh with the rack and that operate the cranks; other pinions mounted free to be displaced axially on part of the crank-shafts; a second rack for actuating the last named pinions; a link arranged to reciprocate with a constant stroke and projecting into the space between the racks; fixed members formed with openings; a pair of carrier-bolts for coupling the racks with the link and arranged transversely to the path of the racks and coaxially one to the other and adapted to project in the reversing position of the racks into the openings of said fixed members; a touching needle; and a slide arranged to move crosswise to the path of the racks and to be operated by the touching needle for axially displacing the carrier-bolts so as to connect one bolt

at one end with one of the racks and at the other end with the link, and the other bolt with the other rack and with one of the fixed members, in order to have only one of the racks slidable and to maintain the other 50 rack in reversing position.

11. An automatic operating mechanism for embroidery machines, of the type in which the simultaneous vertical and horizontal displacements of the frame which jointly determine the shifting thereof are, for each stitch, controlled by means of holes formed in a pattern-strip, said mechanism including a frame-actuating rack; a lever attached thereto; crank-shafts; a series of 60 cranks thereon having different arm-lengths and adjustable, independently of one another, in two positions opposite one to the other, each crank being capable of producing a displacement of the rack corresponding to the throw of the crank; a series of two-armed levers which connect the cranks with the first-named lever and transmit thereto the throws of the cranks; a plurality of hollow shafts carried by the 65 crank-shafts; cranks of unequal length operatively connected with the hollow shafts; levers operatively connected with the last-named cranks; and an adjusting member for a special operation of the embroidery machine, such member being operatively connected with the last-named levers and arranged so that its lift may be varied by the turning of one or more of the hollow shafts the movement of which is transmitted to the 70 adjusting member through the instrumentality of the last-named cranks and levers.

In testimony whereof, I affix my signature in the presence of two witnesses.

OTTO FAHRNI.
